DESIGN FOR A STADIUMETER CHASSIS

Douglas F. Linsley, Greenwich, Conn., assignor to
Schick Incorporated, Stamford, Conn., a corporation of Delaware

Application March 2, 1942, Serial No. 106,053

Term of patent 14 years

To all whom it may concern:

Be it known that I, Douglas F. Linsley, a citizen of the United States, residing in Greenwich, in the county of Fairfield and State of Connecticut, have invented a new, original, and ornamental Design for a Stadiometer Chassis, of which the following is a specification, reference being had to the accompanying drawing, forming a part thereof:

Fig. 1 is a front elevational view of a stadiometer chassis, showing my new design;

Fig. 2, a top plan view; and

Fig. 3, a rear elevational view thereof.

I claim:

The ornamental design for a stadiometer chassis, as shown.

DOUGLAS F. LINSLEY.
